UNITED STATES PATENT OFFICE.

WILLIAM H. GOLDING, OF NEWTON, MASSACHUSETTS.

PRINTING-PRESS.

No. 834,612.

Specification of Letters Patent.

Patented Oct. 30, 1906.

Application filed February 4, 1905. Serial No. 244,209.

To all whom it may concern:

Be it known that I, WILLIAM H. GOLDING, a citizen of the United States, residing at Newton, in the county of Middlesex and 5 State of Massachusetts, have invented new and useful Improvements in Printing-Presses, of which the following, taken in connection with the accompanying drawings, is a specification.

10 My invention relates to the parts of a printing-press which are functionally connected with the movements of the sheets of paper after they have been placed upon the platen and also with their movements in being transferred from the platen to the receiving table or board.

The mechanical features involved in the invention are fully explained in the following description and the accompanying drawings.

15 The drawings consist of a number of figures, of which—

Figure 1 is a side elevation of a printing-press of the type to which I apply my improvements. The parts that are not in some 20 manner connected to or related to my new devices are omitted. Fig. 2 is a plan view of the parts required in the explanation of my invention. Fig. 3 shows in front elevation some of the more essential features. Figs. 4, 25 5, and 6 are enlarged views of details relating to the device for removing the sheets from the platen and depositing the same on the delivery-table. Figs. 7, 8, and 9 are enlarged views of parts relating to the device for adjusting the sheets for printing and for moving 30 them into the field of action of the sheet-removing device. Figs. 10 and 11 show in elevation and plan some of the details connected with the devices for moving the delivery-table.

35 In the drawings the base of machine and other fixed parts are indicated by the letter A and A with attached numerals.

The main driving-shaft is indicated by B, 40 which drives the pinion B' and through it the gear B² and the other parts of the machine. A cam C is affixed to the gear B² and serves to give motion to the rocker-shaft C¹³ through the cam-roller T², lever C³, pivoted at 45 C⁴, adjustable link C⁶ C⁸ C⁷, Fig. 1, pivot-pin C⁹, and rocker-arm C¹⁰, Fig. 2, the said rocker-arm C¹⁰ being adjustably attached to the rocker-shaft C¹³ by the clamps C¹¹ and screw C¹². A long swinging arm D is attached to the rocker-shaft C¹³ and carries at 50

its outer end the sheet-gripping device F⁶ F⁷, moving it forth and back in the arc S, Fig. 2. The rocker-shaft C¹³ is journaled in the parts A³ A⁵ of the frame of the press. A second arm D³, parallel to the arm D, is pivoted to 60 the fixed part A⁴, extending from A³, (see Fig 2,) and is connected at its outer end by the link D² to the outer end of the arm D and serves to hold the gripper in line with the platen. 65

I will now describe the gripper and its connected parts, as particularly illustrated in Figs. 4, 5, and 6. A flat extension d extends from the end of the arm D and has affixed in it a bolt D', which cannot rotate in the extension d, but is made round, so that the link D² can swing freely upon it as the arms D and D³ swing in the arc S. (See Fig. 2.) A cylinder D⁵, connected to the link D², serves as a casing or housing for the swiveling parts of the 70 gripper. A pulley F¹¹ is attached to the bolt D', but does not turn on—that is, it is stationary in relation to the arm D; but the link D² swings about it as a center when the parallels D and D³ swing forth and back, thus 75 causing the cord F¹⁰ to operate the pulley F', thereby turning the grippers F⁷ F⁶, which are mounted on the spindle F about their longitudinal axis. The lower jaw F⁶ of the grippers is made as a part of the pulley F' and 80 spindle F, and the upper jaw F⁷ of the grippers is pivoted at F⁸ to the said lower jaw F⁶. The said pivot F⁸ is rigidly attached to the jaw F⁷, but free to turn in jaw F⁶. The said pivot F⁸ has an arm F¹² inserted in it. The 85 said arm F¹² is so placed that when the parallels D and D³ swing outward, as indicated by the arc S, it comes in contact with the adjustable rod F¹³ on the bracket A⁸ (see Fig. 3) and is thrown forward, causing the pivot-pin 90 F⁸ (see Fig. 4) to make a part rotation, and thus throw the clamping-jaw F⁷ upward, (see dotted lines, Fig. 6,) releasing the sheet of paper held between the jaws F⁶ and F⁷. 95

When the gripper is carried back to the 100 platen, it still remains open until it is in position to seize the printed sheet lying upon the platen. In this position the arm F¹² comes in contact with the end of the arm F¹⁴, which is attached to the eccentric-shaft P'. 105 (See Figs. 1 and 2.) This eccentric-shaft is of ordinary construction and serves to operate the platen P in the usual manner, and is thrown backward, so as to turn the pivot-pin F⁸, and thus close the jaw F⁷, grasping 110

the said printed sheet, and at the next movement of the parallels D and D³ take the sheet over to the delivery-table H¹¹. The gripper is so adjusted that the plane of its jaws 5 coincides with the plane of the platen when about to take the sheet, but as the said gripper retreats with the sheet of paper it is turned by the spring F², which will act as soon as the cord F¹⁰ is slackened by the swinging of 10 the link D², as has been explained.

To hold the gripper open or closed at the right time, the following-described device is used: A V-shaped projection F¹⁵ is formed on the end of the moving jaw F⁷ and is 15 adapted to engage with a similar projection on the end of the sliding bar F³, which is forced outward by the spring F⁴. (See Fig. 6.) A mechanism for moving the sheet into the field of action of the gripper is connected 20 with the registering device, which will be hereinafter explained.

To prevent the arm F¹⁴ from operating to close the gripper when the impression is not being made, it is thrown back by turning 25 the eccentric-shaft P' by the handle P²—that is, the same movement of the eccentric-shaft that moves the platen away from the printing-plate also throws the arm F¹⁴ out of action with the gripper.

30 The delivery-table H¹¹ is moved forth and back longitudinally, but step by step, as the printed sheets are placed upon it, whereby the printed sheets are distributed evenly throughout the length of the table and are 35 better placed for drying and for preventing offset. The said table is supported upon tilting brackets H⁴, which are made fast to the rod H⁷ by set-screws, one of which shown at H⁸, Fig. 10. The rod H⁷ is held 40 loosely in bracket-arms H⁶, which are formed on the sliding bar H³. A spring H¹⁰ is attached at one end by a screw (see Fig. 11) to the rod H⁷ and engages at its other end with the bracket-arm H⁶ and is so arranged 45 that its tendency is to throw the left-hand side of the table down, as shown in full lines in Fig. 10, the projection h resting upon the top of the slide H³. When desired to remove the sheets from the table, it may be tilted, as 50 indicated by the dotted lines in Fig. 10. The slide H³ is constructed to move forth and back in the way-piece H', which is held by screws H² to the bracket-pieces H, which are firmly secured to the fixed rod A⁷. The 55 slide H³, that causes the delivery-table H¹¹ to traverse, is provided with ratchet-teeth H⁵, which are acted upon by the double-acting pawl K⁵ K⁴, which is pivoted to the head-block K³ by the pin K⁶. (See Fig. 11.) The 60 head-block K³ is connected to and operated by the rod K². (See Figs. 11, 1, and 2.) The rod K² is operated by an eccentric K' on the rocker-shaft C¹³ and is connected to the said eccentric by an eccentric-strap K. The pawl 65 K⁴ K⁵, Fig. 11, is so constructed that either

of its two ends may be in working relation to the ratchet H⁵ and is held in either of the positions by the V-shaped projection K¹⁰ engaging with the yielding block K¹¹, which is controlled by the spring K¹². The double 70 pawl K⁴ K⁵ is tilted by the boss K⁷ coming in contact with one of the buttress-pieces K⁸ K⁹, one of which, K⁸, is shown in Fig. 11, and the other, K⁹, is shown in Fig. 2.

The sheet moving, adjusting, and holding 75 device is illustrated in Figs. 2, 7, 8, and 9. In these drawings, R' and R² represent clamping-fingers which are adjustably attached to the rocker-shaft R by thumb-screws R⁶. The rocker-shaft R is of ordinary construction 80 and is adjusted in the usual manner.

The clamping-finger R'—that is, the finger most remote from the delivery-table—has a longitudinal slot R¹⁰, Figs. 7 and 8, which is made for the purpose of making room for the 85 sliding gage-finger G. This gage-finger G has a clip G' for the purpose of assisting in holding the sheets and is connected to a quill G³, which is mounted on the quill R¹¹, which can be moved longitudinally on the rocker-shaft 90 R. The said quill R¹¹ serves as a journal for said quill G³ to slide upon. The said second quill G³ has arms G⁴ G⁵, which have inclined terminals, as shown, which are constructed to operate with the similar inclines on the 95 arms R' R⁸, connected with the clamping-finger R'. A spring G⁶, attached to the collar R⁹, (fixed to the quill R¹¹), serves to hold the moving gage-finger G down onto the platen and also to push the said gage G back on the 100 platen a little removed from the place on the platen P that would be occupied by the edge of the sheet to be printed. When the clamping-finger R' is raised up, as indicated in Figs. 7 and 9, then the moving gage G is forced 105 back away from the position at the edge of the sheet to be printed; but when the clamping-finger R' is coming down to its sheet-holding position, as shown in Fig. 8, then the moving gage G is forced forward (by the inclines R⁷ and R⁸ acting on the inclines G⁴ G⁵) 110 against the edge of the sheet to be printed and in its forward movement forces the said sheet into the exact position for printing and also into the field of action of the gripper 115 F⁷ F⁶.

The clamping-finger R' has attached to it an auxiliary adjustable arm R³, held by a thumb-screw R⁴, which works through a slot R⁵. (See Figs. 7 and 8.)

The outer edges of the clamping-fingers R' R² are serrated for the purpose of retaining sheet-holding cords in any desired places.

The rocker-arm C¹⁰, which operates the rocker-shaft C¹³, is operated by the adjustable link C⁶ C⁸ C⁷, thereby regulating the extent of movement of the gripper-frame and the gripper and insuring the gripping of the paper at the desired point.

The rod F¹³, which opens the gripper, is ad- 130

justable on the arm A⁸ both as to its length and position, so that it may always be in position to open the gripper. A buffer A⁹, made of leather or some other suitable material, is attached to the arm A⁸, Fig. 3, and is intended to receive the stroke of the gripper-swinging frame and check it without shock.

Although I have shown in the drawings and described in the specification the registering-gage and its connecting parts, also the serrated-edged clamping-finger and its functionally-connected part, and the peculiar means for operating the delivery-table and the delivery-table itself, I do not claim them in this application, as I reserve the subject-matter involved in these parts for separate application.

I claim—

1. In a printing-press, a lateral-delivery device, consisting of a vertical rocker-shaft and means for operating the same: parallel arms one of which is attached to and operated by the said rocker-shaft, the other parallel arm being attached to a stationary bracket: a link connecting the swinging ends of the said parallel arms and having a gripper connected to it, constructed to grip the printed sheet and take the same to the delivery-table: substantially as and for the purpose set forth.

2. In a printing-press, a laterally-delivering device consisting of a vertical rocker-shaft and means for operating the same; parallel arms forming a part of a horizontal frame attached to and operated by the said rocker-shaft; a link connecting the swinging ends of the said parallel arms and having a gripper connected to it, and said gripper mounted upon a swiveling spindle whereby the said gripper may turn upon its longitudinal axis, and means for turning said gripper; substantially as and for the purpose set forth.

3. In a printing-press, a lateral-delivery device, consisting of a vertical rocker-shaft and means for operating the same: parallel arms forming a part of a horizontal frame attached to and operated by the said rocker-shaft: a pulley fixed to a stud on the swinging end of one of the said parallel arms: a link, one end of which has a rotative motion about the said pulley, the other end of the said link being attached to the swinging end of one of the said parallel arms: a gripper connected to said link and having a rotative motion on its spindle: a cord connecting said pulley and gripper, whereby the said gripper is given a rotative motion: substantially as and for the purpose set forth.

4. In a printing-press, a platen for holding the sheets to be printed; a sheet-moving gage constructed to move the sheet laterally into the field of action of the gripping device; a laterally-operating gripping device constructed to seize the said sheet and draw the same laterally from the said platen and place it upon the delivery-table and a laterally-

located delivery-table; substantially as and for the purpose set forth.

5. In a printing-press, a platen adapted to hold the sheets to be printed and having a sheet-moving gage adapted to move upon the face of the said platen against the sheet to be printed and to move the said sheets into the field of action of the laterally-operating gripping device, and said gripping device; substantially as and for the purpose set forth.

6. In a printing-press, a platen adapted to hold the sheet and having a laterally-operating sheet-moving gage; a gripping device adapted to seize the sheet and draw it to the delivery-table, means for laterally moving said gripping device to the delivery-table, and means for opening the said gripping device, thereby leaving the sheet free to be deposited on the table; substantially as and for the purpose set forth.

7. In a printing-press, a platen adapted to hold the sheet and having a paper-moving gage; a laterally-operating paper-gripping device adapted to receive the paper, and means for moving said gripping device laterally over to the delivery-table, and means for opening the said gripping device, thereby leaving the sheet free to be deposited on the table; an automatically-moved delivery-table at the side of the press, for receiving the said paper and means for operating the said table, step by step in one direction and then step by step in the other direction, whereby the printed sheets are distributed evenly throughout its length; substantially as and for the purpose set forth.

8. In a printing-press, a platen adapted to hold the sheets, a gripping device moving in a horizontal plane and adapted to seize the paper, said gripping device having a swinging motion whereby the paper is carried laterally from the platen toward the delivery-table and also a partial rotating motion whereby the paper is turned so as to be laid flat upon the delivery-table, and means for swinging and turning the said gripping device.

9. In a printing-press, a platen adapted to hold the sheets, a gripping device adapted to seize the paper, said gripping device moving in a horizontal plane and having a swinging motion whereby the paper is carried to the delivery-table, and means for swinging and turning the said gripping device.

10. In a paper-delivery device, a gripper comprising a jaw fixed to a spindle with which it turns; a moving jaw having a pivot by which it is joined to the fixed jaw, the said pivot being rigidly attached to the moving jaw whereby any movement of the said pivot will cause a like movement of the said moving jaw; an arm inserted in said pivot and constructed to be operated by fixtures attached to the frame of the machine;

and said fixtures; and means for holding said moving jaw temporarily open or closed; substantially as and for the purpose set forth.

11. In a printing-press, a gripper and a swinging frame constructed to operate said gripper and a rocker-shaft adapted to operate said swinging frame; and means for adjusting the movement of the said rocker-shaft, whereby the said gripper is adjusted to the margin of the paper on the platen; substantially as and for the purpose set forth.

12. In a printing-press, a gripper and a horizontally-operating swinging frame constructed to operate said gripper as described; a rocker-shaft constructed to operate said swinging frame; a link constructed to operate said rocker-shaft; and means for adjusting the length of the said link whereby the throw of the said gripper is regulated; substantially as and for the purpose set forth.

13. In a printing-press, a gripper constructed to take the paper laterally from the

platen, and an adjustable gripper-opening rod adapted to open the said gripper at the point of delivery; substantially as and for the purpose set forth.

14. In a printing-press, a gripper constructed to take the paper from the platen when the same has received its impression; a movable gripper-closing device attached to the eccentric that throws the platen into and out of "impression," and the said platen and eccentric whereby when the platen is not in working position the said gripper-closing device does not act upon the said gripper; substantially as and for the purpose set forth.

In testimony whereof I have signed my name to this specification, in the presence of two subscribing witnesses, on this 2d day of February, A. D. 1905.

WILLIAM H. GOLDING.
